(57) **CLAIM**

The ornamental design for an earring as shown and described.

DESCRIPTION

1. Earring

1.1 : Perspective

1.2 : Front

1.3 : Back

1.4 : Top

1.5 : Bottom

1.6 : Right

1.7 : Left

The characteristic features of the design reside in the shapes as shown in the reproductions; the broken lines shown in the reproductions illustrate portions of the earring and form no part of the claimed design.
